UNITED STATES PATENT OFFICE.

ALPHEUS D. SMITH, OF GRAFTON, OHIO.

IMPROVEMENT IN REIN-GUIDES FOR VEHICLES.

Specification forming part of Letters Patent No. 142,127, dated August 26, 1873; application filed February 17, 1873.

To all whom it may concern:

Be it known that I, ALPHEUS D. SMITH, of Grafton, in the county of Lorain and State of Ohio, have invented a Rein-Guard, of which the following is a specification:

The nature of my invention consists in the employment of a rein-guard, so constructed and arranged in combination with the thills as to prevent the horse from being able to catch the rein or reins under his tail, thereby giving additional security to life, limb, and property, as hereinafter more fully set forth, and shown by the annexed drawing and letters of reference marked thereon, in which—

A, B, and C are perspective views of parts combined.

My rein-guard B may be constructed from an ordinary rod or strap, of any suitable material, size, and length. Either one or both ends of the same may be rigidly or adjustably secured to the thills A or other convenient parts, as shall at all times hold the rein or reins at such distance as will prevent the horse

from being able to catch the rein or reins under his tail. The height of the guard B above the thills A A depends upon its length, which may be sufficient to admit of any necessary adjustment up and down. The rein-guard may be made with or without the loop or ring C, which is for the purpose of retaining the reins, which may be passed through it, at a safe distance from being caught and at any given point. By the employment of guard B, which extends up and across from thill to thill, the reins are held off from the horse and from liability of being caught by any part of the harness or whiffletree, and requires no extra adjustment of the reins by its use.

I claim as my invention—

The rein-guard B, applied to the shafts A, substantially in the manner shown and set forth.

ALPHEUS D. SMITH.
